CLAIM

The ornamental design for cabinet for video distance learning system, as shown and described.

DESCRIPTION

FIG. 1 is a front elevational view of a cabinet for video distance learning system showing our new design;
FIG. 2 is a left side elevational view thereof;
FIG. 3 is a right side elevational view thereof;
FIG. 4 is a rear elevational view thereof;
FIG. 5 is a front perspective view thereof, as seen from the bottom right; and,
FIG. 6 is a top plan view thereof.
